UNITED STATES PATENT OFFICE

130,673

DESIGN FOR A MUSIC RACK

John E. Kluson, Chicago, Ill., assignor to The
Norwood Company, Chicago, Ill., a corpora-
tion of Illinois

Application December 6, 1939, Serial No. 88,723

Term of patent 14 years

To all whom it may concern:

Be it known that I, John E. Kluson, a citizen
of the United States, residing at Chicago, in the
county of Cook and State of Illinois, have in-
vented a new, original, and ornamental Design
for a Music Rack, of which the following is a
specification, reference being had to the accom-
panying drawing, forming a part thereof.

In the drawing:

Figure 1 is a perspective view of a music rack
showing my new design; and

Figure 2 is a vertical transverse section taken
on the line 2—2 of Figure 1.

The dominant features of my new music rack
design are shown in full lines in the drawing.

I claim:

The ornamental design for a music rack, as
shown and described.

JOHN E. KLUSON.
